UNITED STATES PATENT OFFICE.

CLARENCE GLADSTONE WAUDBY, OF JACKSON, MICHIGAN.

ROTARY TOOTH-BRUSH.

1,193,644.

Specification of Letters Patent.

Patented Aug. 8, 1916.

Application filed September 22, 1915. Serial No. 51,973.

To all whom it may concern:

Be it known that I, CLARENCE GLADSTONE WAUDBY, a citizen of the United States of America, residing at Jackson, in the county of Jackson and State of Michigan, have invented certain new and useful Improvements in Rotary Tooth-Brushes; and I do hereby declare the following to be a full, clear, and exact description of the invention, such as will enable others skilled in the art to which it appertains to make and use the same.

This invention relates to a rotary brush in which a brush is operated back and forth a number of revolutions through the medium of a manually operated plunger forming a part of the mechanism of the brush.

It is an object and purpose of my invention to provide a device of this character of very simple and economical construction and to equip said device with many novel details of construction and arrangement of parts for the attainment of a very durable and efficient brush which may be readily and easily operated and used for a long period of time without liability of the parts getting out of order. To these ends I have provided the embodiment illustrated in the accompanying drawing, in which:—

Figure 1 is a vertical section taken longitudinally of the brush. Fig. 2 is a side elevation thereof. Fig. 3 is a view looking toward the left end of Fig. 2. Fig. 4 is a sectional view on the line 4—4 of Fig. 2; and Figs. 5, 6 and 7 are sections taken, respectively, on the lines 5—5, 6—6 and 7—7 of Fig. 1 looking in the direction indicated by the arrows.

Like reference characters refer to like parts throughout the several views of the drawing.

In the construction of my improved brush there is provided a tubular member 1 in which a tubular plunger 2 telescopes, this latter member at its end having a head 3 secured in any suitable manner while the first member 1 is provided with a curved finger hold 4. In operation the plunger 2 is forced inwardly against a spring 5 which is inclosed within tube 1 by the operator placing his thumb upon the head 3 and the first finger around the finger hold 4. The end of the member 1 is equipped with a screw threaded cap 6 which has an opening 55 for the passage of the plunger 2 and which is knurled as shown to add to the appear-

ance of the device. At its opposite end the member 1 receives a collar 7 which serves as a bearing for the shaft 8 passed therethrough and which is formed from wire doubled and twisted together as shown, this wire passing the length of the tube 1 and through a slot 9^a in a collar 9 secured at the inner end of the plunger 2. It will be apparent that as the plunger is forced into the tube 1 the shaft 8 is made to rotate, in this manner turning the cylindrical brush 10 which is positioned at the end of the shaft 8 beyond the tube 1, a disk 10^a secured to the shaft 8 and normally bearing against the collar 7 and the end of the tube 1 serving to keep the bristles of the brush from entanglement with the collar. Shaft 8 at its outer end is formed with a rounded head which seats in a bearing 11 pressed in the end of shield 12 normally covering the upper portion of the brush, being pivotally connected by the pivot pin 13 to a collar 14 secured at the end of the tubular member 1. In practice a collar 15 fits over collar 14 and bears against a shoulder of the shield holding it in its operative position, but if desired, this collar may be moved to the rear and the shield turned about its pivot after disengagement from the shaft 8 to permit the removal of the brush and shaft for cleaning or for replacement by a new brush whenever desired. The collar 15 is also knurled to add to the appearance and the finger hold 4 and head 3 may be given any desired ornamental appearance.

This construction is very simple, requiring but few parts which may be easily and economically manufactured. When the tube 2 is pressed inwardly the brush is rotated rapidly in one direction and when the release of pressure on the head 3 occurs spring 5 forces the tube outwardly, the brush rotating in the opposite direction.

I claim:—

1. In combination, a tubular member, a plunger telescoping therein, a spring in said member normally resisting the entrance of the plunger, a shaft having a brush on one end inserted in the tubular member and into the plunger, means to automatically rotate the shaft on movements of the plunger, a shield pivotally carried by the tubular member adapted to partially cover the brush and a bearing in the shield for one end of the shaft, said bearing being moved away from the shaft on pivotal movement of the

shield, thereby freeing the shaft for removal.

2. In combination, a tubular member, a spring therein, a finger hold on said member, a plunger inserted in said member and bearing against the spring, a bearing in one end of the tubular member, a spirally formed shaft mounted in the bearing extending through the spring into the plunger, means carried by the plunger for automatically rotating the shaft as the plunger moves with reference to the tubular member, a shield pivotally mounted on said tubular member having a bearing for the end

of the shaft, and a brush on the shaft partially inclosed by the shield.

3. In combination, a tubular member, a shaft removably mounted therein, a shield pivotally mounted on the tubular member, a brush on the shaft partially inclosed by the shield, a bearing in the shield receiving the end of the shaft, and means to manually rotate the shaft and brush, substantially as described.

In testimony whereof I affix my signature.

CLARENCE GLADSTONE WAUDBY.
